DEVICE FOR FORMING AND APPLYING
BOBBY PINS TO FLAT CURLSWilliam F. Feyrer, Englewood, N. J., assignor to
Nathan L. Solomon, Englewood, N. J.

Application June 23, 1949, Serial No. 100,844

5 Claims. (Cl. 132—33)

1

This invention relates to devices for forming what is known as flat pin or sculpture curls and for simultaneously attaching a pair of bobby pins to the curl to maintain the same in the flat extended position. More particularly, the invention deals with a device of the character described comprising a pair of jaw-like plate members within and between which a curl is formed, the jaw plate members having means for supporting a pair of bobby pins thereon, the pins being utilized as tensional means to maintain the jaws in closed position.

Still more particularly, the invention deals with a device of the character described having means for displacing the pins from the jaws for attachment to the formed curl.

The novel features of the invention will be best understood from the following description, when taken together with the accompanying drawing, in which certain embodiments of the invention are disclosed and, in which, separate parts are designated by suitable reference characters in each of the views and, in which:

Fig. 1 is a longitudinal sectional view through a device made according to my invention.

Fig. 2 is a plan view of the structure, as seen in Fig. 1.

Fig. 3 is a section on the line 3—3 of Fig. 2; and

Fig. 4 is a view similar to Fig. 3 with parts in a different position.

In practice, I provide a curler device comprising two plate-like jaw members 10 and 11, having depending wall portions 12 and 13, respectively, pivoted together, as seen at 14. Beyond the pivot 14, the members 10 and 11 have diverging fingerpiece portions 15 and 16. The jaw member 10 has an integral split sleeve portion 17 having an inturned annular stop flange 18 at its outer end. Within the sleeve portion 17 is disposed a hair curling element 19 having a lower split end 20 and an outer enlarged knurled head 21. The element 19, inwardly of the split end 20, has an annular stop shoulder 22 co-operating with the flange 18 to check outward movement of said element, the head 21 checking movement of the element in the opposite direction. By providing a split sleeve 17, the element 19 can be forcibly mounted in the sleeve, as will be apparent. The outer end of the sleeve 18 has an outwardly burred or turned flange 23 for retaining a rotary cam 24 against displacement from the sleeve 17. The cam 24 has diverging cam portions 25 normally disposed longitudinally of the member 10, as seen in full lines in Fig. 2. 55

2

Side edges of the member 10 have shallow grooves or recesses, as at 26. The member 11 has deeper corresponding grooves, as at 27. These grooves provide means for mounting bobby pins 28 upon the members 10 and 11 to normally support side edge portions thereof in abutting relationship to each other, as seen in Fig. 3 of the drawing.

The jaw member 11 has, in alignment with the sleeve 17, a depressed portion 29 for reception of the lower split ends 20 of the element 19.

The depressed portion 29 is formed in a longitudinally recessed portion 30 of the jaw member 11 providing slight clearance between adjacent surfaces of the jaws 10 and 11 for starting a swatch of hair in the split end 20 of the element 19, preparatory to forming the curl.

After a swatch of hair has been inserted into the device between the jaw members 10 and 11, 20 as indicated diagrammatically by the swatch of hair 31 in Fig. 1, a pair of bobby pins 28 are attached to the jaw members by seating in the recesses 26—27, as clearly seen in Fig. 3, and also indicated in Fig. 2. Then the element 19 25 is rotated to form the curl thereon. Incidentally, the element 19 might be partially rotated in the initial operation to hold the end of the curl and, after the curl has been formed, in which operation the jaw members 10 and 11 will be spread 30 to a slight extent against the spring action of the bobby pins, the bobby pins can then be detached from the members 10 and 11 by rotating the cam 24 which will displace the bobby pins from the jaw members and move them into engagement with side portions of the flat curl, as 35 indicated in dot and dash lines at 32 in Fig. 2 of the drawing. In other words, the cam members 25 simply slide the bobby pins off the groove side edges of the members 10 and 11 and they 40 will then snap into engagement with the flat curl or the portions 33 thereof extending beyond side edges of the jaw members.

It will be understood that the showing in the accompanying drawing is somewhat diagrammatic and the jaw members 10 and 11 will be made comparatively narrow so as to keep within bounds of side edges of the formed flat curl.

After the bobby pins have been attached to the curl, the element 19 is raised to free the flat curl and the jaw members can now be freely separated for removal from the curl with the bobby pins thereon.

In the accompanying drawing, the bobby pins are shown mounted with the closed ends thereof adjacent the pivot of the jaw members. It will

be understood, however, that the bobby pins can be reversely mounted, in which latter instance, the pins or the spread end portions only thereof need be attached to the groove portions of the jaw members, after which the formed curl can be moved by hand along the jaw members into the bobby pins, at which time, the pins will be released for clamping engagement onto the curl.

In the use of the invention as disclosed in the drawing, the bobby pins are displaced onto the curl, while the curl remains in position between the jaws, after which the jaws are removed from the clamped curl.

Having fully described my invention, what I claim as new and desire to secure by Letters Patent is:

1. A device for forming and clamping flat curls, said device comprising a pair of pivotally coupled elongated jaw members, side edge portions of said jaw members being in common alignment and in abutting relationship in the normal position thereof, at least one of said jaw members having shoulder forming means adjacent said side edges adapted to aline a pair of bobby pins with said side edges when said pins are mounted on said device in clamping engagement with outer surfaces of said jaw members, a curl forming element rotatably mounted in one jaw member and having a notched hair engaging portion registering with bearing forming means in the other jaw member, and bobby pin ejector means movably supported on said device and adapted in one position thereof to extend laterally beyond said shoulder forming means and to the said edges of said jaw members, whereby bobby pins supported on said device can be laterally displaced therefrom into clamping engagement with a flat curl formed between said jaw members.

2. A device as defined in claim 1 wherein the bobby pin ejector means comprises a rotatable cam.

3. A device as defined in claim 1 wherein the bobby pin ejector means comprises a rotatable cam member mounted on a common axis with said curl forming element and having opposed cam surfaces for simultaneously displacing bobby pins from opposed side edges of the device.

4. In a flat curl forming device comprising

opposed plate members having registering straight side edge portions and a curl forming element rotatably mounted on one of said members for formation of a flat curl between said members, shoulder forming means adjacent the straight side edges of at least one of said plate members for alining a pair of bobby pins with said side edges when such pins are mounted for clamping engagement with outer surfaces of said plate members, and movable means on said device adapted in one position thereof to protrude beyond said shoulder forming means and to said straight side edges whereby the bobby pins supported on said device can be displaced therefrom into clamping engagement with a curl formed between said plate members.

5. In a flat curl forming device comprising opposed plate members having registering straight side edge portions and a curl forming element rotatably mounted on one of said members for formation of a flat curl between said members, shoulder forming means adjacent the straight side edges of at least one of said plate members for alining a pair of bobby pins with said side edges when such pins are mounted for clamping engagement with outer surfaces of said plate members, and a rotatable cam on said device adapted in one position thereof to protrude beyond said shoulder forming means and to said straight side edges, said cam having opposed cam surfaces, whereby the bobby pins supported on said device can be simultaneously displaced therefrom into clamping engagement with a curl formed between said plate members.
